(57) **CLAIM**

The ornamental design for a headlight for automobile, as shown and described.

DESCRIPTION

FIG. 1 is a front and right perspective view of a headlight for automobile, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The claimed design is indicated by the relatively dark portion, while the relatively light and blurred portions are environmental and form no part of the claimed design.
